UNITED STATES PATENT OFFICE.

CHRISTIAN JOHANN GEORG SCHWARZ, OF OFFENBACH-ON-THE-MAIN, GERMANY.

FASTENER FOR THE MOUTH FRAMES OF HAND BAGS.

Application filed October 11, 1926, Serial No. 140,898, and in Germany August 25, 1926

My invention relates to fasteners for the mouth frames of hand bags, portmanteaus and the like and it is an object of my invention to provide improved means for closing the mouth frame. To this end I combine the usual spring catch with a fastening pawl in such manner that the fastening pawl is placed in operative position by turning the usual button-shaped handle of the spring catch through a given angle for instance, through 90°.

The usual arrangement of the handle for closing a bag or the like of the kind described is at the central portion of the mouth frame. Heretofore, the means for closing the frame were often very complicated and frequently combined with a safety catch but these complicated devices were abandoned because they were too expensive and not reliable. Modern tendency is to simplify the closing and fastening means. At present, the closing device which is most frequently employed is the so-called spring catch comprising a handle which is resiliently hinged or otherwise connected with one of the mouth bars and when closed engages a projection on the other bar by means of a tooth or a recess.

This spring catch is simple, cheap and durable but it lacks reliability because heretofore it could not be provided with a suitable safety fastener so that it often opens of its own account so that objects were lost from the bag.

In my invention this drawback is overcome by providing a simple and reliable safety fastener in connection with the normal spring catch.

In the drawings affixed to this specification and forming part thereof devices embodying my invention are illustrated diagrammatically by way of example.

In the drawings

Fig. 1 is an elevation,

Fig. 2 is a front end elevation of a mouth frame provided with my improved closing device,

Figs. 3 to 6 illustrate details of the closing device on a larger scale.

Fig. 3 is a section of the closing device in the axis of its operating pintle,

Fig. 4 is a plan view of the device,

Fig. 5 is an elevation of its pintle viewed at right angles with regard to Fig. 3, and

Fig. 6 is an elevation illustrating a modified safety fastener.

Referring now to the drawings, *a* and *b*

are the two bars of the mouth frame which are connected by hinges *c*, *c*. Obviously, instead of being substantially semi-circular as shown, the bars may be of any suitable configuration and cross-section.

The closing device is arranged on the bar *a* and comprises the pintle *d* and a handle *e* which is rotatably carried on the pintle. It will be understood that this handle which is shown in the usual form of a button, may be of any desired configuration. The pintle *d* extends into a cavity *f* of the handle *e* which is closed by a plate *g*, and a square *h* at the upper end of the pintle projects into the cavity *f*. Flat springs *k* and *i* are secured with their ends and slots in the walls of the cavity *f* so as to engage opposite faces of the square *h*. A washer *l* is placed on the pintle above the square *h* and secured by riveting over its end *m*.

In this manner the handle *e* is held with regard to the pintle in four positions corresponding to the four sides of the square *h*. Rotation of the pintle is prevented by a buckle *o* on a head *n* at the lower end of the pintle which buckle is perforated and a spring *p* is inserted in its perforation.

q is a recess in the head *n* which is adapted to be engaged by a projection *r* on the bar *b* when the bag is closed.

The spring *p* holds the base *s* of the handle *e* in position on the bar *a*. By tilting the handle *e* to the left in Fig. 2, the recess *q* will be caused to release the projection *r* on the bar *b* but such release is prevented by two pawls *t* on the bar *a*. The base *s* is not circular but has its maximum extension in the direction of the sectional plane in Fig. 3 so that by turning the handle through 90° the projections at the ends of the base will be placed out of reach of the pawls *t*, *t* so that the handle *e* is free to be tilted against the action of the spring *p*, causing the recess *q* in the pintle to release the projection *r* of the bar *b*, as described.

Referring now to Fig. 6, this modification is substantially similar to the one described but in this case the pawls *t*, *t* are dispensed with and instead a plate *u* is secured to the bar *b* which is slotted at *v* for the reception of one of the projecting ends of the base *s*.

Obviously, I am not limited to a square head *h* on the pintle *d* but I may provide a head of any suitable polygonal area or a substantially cylindrical head with flat faces adapted to be engaged by a spring or any

number of springs, and in general I wish it to be understood that I do not desire to be limited to the exact details of construction shown and described for obvious modifications will occur to a person skilled in the art.

I claim:—

1. A fastener for mouth frames for hand bags, portmanteaus and the like comprising two bars, a pintle secured on one of said bars 10 and adapted to be tilted thereon, a catch on said pintle, a counterpart to said catch on the other bar, a handle rotatably seated on said pintle, a pawl on said first-mentioned bar, and a part on said handle which is adapted to be retained by said pawl in a given position of said handle so as to prevent tilting of said pintle and to be released after said handle has been rotated out of this given position.
2. A fastener for hand bags, portmanteaus and the like the mouth frame of which has two bars, comprising a pintle secured on one of said bars and adapted to be tilted thereon, a polygonal part on said pintle, a handle rotatably seated on said pintle, a spring in said handle adapted to engage one of the faces of said polygonal part so as to hold said handle in a given position, a catch on said pintle, a counterpart to said catch on the other bar, a pawl on said first-mentioned bar, and a part on said handle which is adapted to be retained by said pawl in a given position of said handle, so as to prevent tilting of said pintle, and

to be released after said handle has been rotated out of this given position.

3. A fastener for hand bags, portmanteaus and the like, the mouth frame of which has two bars, comprising a pintle secured on one of said bars and adapted to be tilted thereon, a square part on said pintle, a handle rotatably seated on said pintle, a spring in said handle adapted to engage one of the faces of said square part, so as to hold said handle in a given position, a catch on said pintle, a counterpart to said catch on the other bar, a pawl on said first-mentioned bar, and a part on said handle which is adapted to be retained by said pawl in a given position of said handle, so as to prevent tilting of said pintle, and to be released after said handle has been rotated out of this given position.

4. A fastener for hand bags, portmanteaus and the like, the mouth frame of which has two bars, comprising a pintle secured on one of said bars and adapted to be tilted thereon, a catch on said pintle, a counterpart to said catch on the other bar, a handle rotatably seated on said pintle, a pawl on said first-mentioned bar, and a projection on the base of said handle which is adapted to be retained by said pawl in a given position of said handle, so as to prevent tilting of said pintle, and to be released after said handle has been rotated out of this given position.

In testimony whereof I affix my signature.

CHRISTIAN JOHANN GEORG SCHWARZ.
